(57) **CLAIM**

The ornamental design for a magnetic cell as shown and described.

DESCRIPTION

FIG. 1 is a top perspective view of a magnetic cell in accordance with this invention.

FIG. 2 is a top plan view of the magnetic cell of FIG. 1.

FIG. 3 is a bottom plan view of the magnetic cell of FIG. 1.

FIG. 4 is a front view of the magnetic cell of FIG. 1.

FIG. 5 is a rear view of the magnetic cell of FIG. 1.

FIG. 6 is a left side view of the magnetic cell of FIG. 1; and,

FIG. 7 is a right side view of the magnetic cell of FIG. 1.

Broken lines included in the drawings show portions of the article that form no part of the claimed design.
